**MERRY-GO-ROUND FOR PLAYGROUNDS
AND THE LIKE**

Robert L. Propst, Englewood, Colo., assignor to Beauty Products, Ltd., Denver, Colo., a corporation of Colorado

Application August 8, 1956, Serial No. 602,753

7 Claims. (Cl. 272—42)

This invention relates to playground equipment, and more particularly to elevating merry-go-rounds.

For many years merry-go-rounds have been known which provide a frame mounted on an upright pole for both rotational and upward and downward movement relative thereto. The frame is customarily suspended from the top of the pole by a plurality of angularly spaced ropes or the like which twist around the pole and raise the frame as it is rotated. These devices have enjoyed little commercial success or public acceptance, however, because of certain structural limitations that render them quite difficult for children to use.

Among these limitations is the fact that the conventional merry-go-round of this type employs only a single ring-like frame which becomes elevated so rapidly as the ropes twist around the pole that the children can no longer impart the required rotational momentum thereto. Or, in other words, the frame rises up the pole so fast that the children's feet leave the ground before they can get the frame rotating rapidly. Moving the ring closer to the ground is of little help in solving this problem as a ring or frame mounted low to the ground often causes the children to trip and fall as they run to get it started and may result in serious injury.

Another problem associated with the prior art designs is that it is extremely difficult to get the ring or frame rotating after it has come to rest. This results because the weight of the frame and the downward force exerted thereon by the children as they attempt to rotate it are in direct opposition to the forces required to twist the ropes around the pole and lift the frame. As the ropes twist about the pole and the frame becomes elevated, the downward pull on the frame by the children increases and acts to unwind rather than wind the ropes about the pole. Obviously, this fact quickly slows down the rotation of the frame, causes it to stop and begin rotating in the opposite direction before the intended elevation of the frame has been realized.

It has now been found, however, in accordance with the present invention, that the foregoing problems can be overcome by incorporating certain improved features that permit the children to take advantage of centrifugal force to aid them in realizing the full potentialities of an elevating merry-go-round. In addition, the improved merry-go-round described and claimed herein embodies a novel bearing between the frame and pole which eliminates the possibility of a child being injured by placing his hand on the bearing while the frame is rotating.

It is, therefore, the principal object of the present invention to provide an improved elevating merry-go-round which is considerably easier to start than those heretofore known, which permits higher rotational speeds to be attained and which permits children of various sizes to enjoy the device.

Still a further object is to provide a merry-go-round of the type described wherein there is provided a lost motion connection between the frame and pole whereby the frame may be rotated a complete revolution relative to

the pole before the ropes or connectors begin to wind on the pole and raise the frame.

Another object of the invention is to provide an improved safety bearing between the frame and pole.

Additional objects of the invention are to provide an elevating merry-go-round which is simple, relatively inexpensive, rugged, safe and easy to use.

The construction designed to carry out the invention will be hereinafter described, together with other features thereof, and will be more readily understood from a reading of the following specification and by reference to the accompanying drawings forming a part thereof wherein an example of the invention is shown and wherein:

Figure 1 is an elevation showing the improved elevating merry-go-round of the present invention;

Figure 2 is a section taken along line 2—2 of Figure 1 showing the bearing detail to an enlarged scale;

Figure 3 is a top plan view of the merry-go-round; Figure 4 is a section taken along line 4—4 of Figure 1; and

Figure 5 is an enlarged diametrical section illustrating a modified form of hub embodying a lost motion connection.

Referring now in particular to Figure 1 of the drawing, the improved elevating merry-go-round of the present invention will be seen to comprise a frame, indicated in a general way by numeral 10, mounted on an upright pole 12 for both rotational and upward and downward movement relative thereto, and a plurality of angularly spaced flexible connectors 14 by which the frame is suspended from the top of the pole. The pole 12 is preferably set in a concrete base 16 which is in turn set into the ground 18 with the pole projecting upwardly therefrom substantially vertically. The pole rises several feet above ground level and is provided with a cap 20 on the upper end thereof. A plurality of upturned hooks 22, one for each connector, are welded or otherwise permanently attached to the cap in equiangularly spaced relation. The upper end of each connector 14, a chain in the particular embodiment illustrated, is connected to a hook and hangs downwardly therefrom. Five flexible connectors have been shown, although as few as three may be used.

In Figures 1, 3 and 4 the frame 10 will be seen to comprise a large ring 24, a small ring 26, a bearing 28, and struts 30 and 32. The bearing 28 is journaled for rotation on pole 12, as well as upward and downward sliding movement relative thereto and will be described in detail in connection with Figure 2 of the drawing. Large ring 24 is mounted in concentric relation about the pole and is attached to the bearing for conjoint rotation by radial struts 30, five of which are shown. The struts 30 are preferably inclined upwardly in the manner indicated which places the large ring in a substantially horizontal plane above the bearing. The smaller ring 26 is mounted in spaced concentric relation beneath the large ring and is supported by stub struts 32 extending between the small ring and struts 30. The large ring 24 is provided with semi-circular metal elements 34, shown in Figure 3, welded to the ring at the points of attachment of struts 30. The lower ends of the flexible connectors 14 are attached to elements 34.

As indicated by dotted lines in Figure 1, the frame will rise on the pole when rotated as the connectors 14 will twist about the pole, shorten, and elevate the frame with respect to the ground. In the embodiment of Figures 1 through 4, inclusive, the cap, hooks and upper ends of the chain are fixed relative to the pole and cannot rotate.

The first important improvement embodied in the elevating merry-go-round of the present invention is the

provision of two vertically spaced rings in the frame. The large ring is located a convenient distance above ground level, when the connectors are fully extended as shown by full lines in Figure 1, to be grasped for imparting the initial rotary motion to the frame in the conventional manner. Generally, however, the large ring will be elevated to a height where the children's feet begin to leave the ground before the desired speed of rotation necessary to raise the ring to the top of the pole is attained. At this point the second or small ring has become elevated to a height above the ground where it can be conveniently grasped and used as a means for producing the additional rotational speed required to accomplish the desired elevation of the frame. Thus, the provision of the second ring below the first enables the frame to be rotated and elevated in two stages, thereby permitting higher rotational speeds to be attained which, by reason of centrifugal force, will cause the frame to rise higher upon the pole. An added feature of the second ring and the reason for its being somewhat smaller is that it permits the younger children to enjoy the device and play on it at the same time it is being used by older children.

Now referring to Figure 2 of the drawing, the novel construction of the bearing 28 will be described. The bearing comprises a tubular section 36 mounted in concentric relation on the pole 12 and sized to provide an annular space 38 therebetween. A wooden ring 40 is positioned between the outer surface of the pole and the inner surface of the tubular section approximately midway between the ends of said tube as shown. The wooden ring is attached to the tubular section by suitable fasteners 42 and forms a bearing block in contact with the pole. The annular space 38 between the pole and tube is sized to receive the hand of a child without being pinched or caught between the relatively movable parts. The portion of the tube projecting above and below the wooden ring is such that it is extremely difficult for a child to reach his hand in far enough to contact the ring or bearing block where he could be seriously injured. As a further precaution, the upper and lower ends of the tube are closed by heavy rubber sealing members 44 that are bolted to the tube and extend across the annular space. This bearing structure protects the children from painful injury should they attempt to place their hands in the bearing while the frame is revolving on the pole.

Another important feature of the instant device has been illustrated in Figure 5. In this slightly modified construction pole 12a is provided with an upwardly projecting frusto-conical tip 46 terminating in a threaded section 48. Roller bearings 50 and 52 are mounted on the tapered surface of the tip in vertically spaced relation and modified cap member 20a is mounted for rotation thereon. Cap 20a has an opening 54 in its upper end sized to receive threaded section 48 and nut 56 holds the cap in place on the tip. The cap 20a is hollow, open at the lower end, and provided with an annular shoulder 62 spaced below the top 60. Roller bearing 52 rests against the shoulder which holds the top of the cap spaced above the upper end of the tip. A second shoulder 64 is formed inside the cap to rest upon lower roller bearing 50.

Integrally formed with the cap 20a is an annular flange or apron 66 projecting laterally from the pole 12a. Eye bolts 68 are carried in the periphery of the apron and function in the same manner as hooks 22 of the Figures 1 through 4 modification. The flange or apron also carries a pin 70 adjacent the cap and positioned to engage stop 72 on the upper end of the pole upon relative rotation therebetween. Thus, the cap 20a is free to rotate relative to the pole 12a a maximum of one complete revolution before the pin 70 engages the stop 72. Essentially the cap, pin and stop function as a lost motion connection which permits the frame to be rotated

a complete revolution relative to the pole before the connectors begin to wind on the pole and raise the frame. Here again, the lost motion connection provides a means by which the frame may be rotated fast enough to carry it to the top of the pole before the children's feet leave the ground. The most important advantage, however, is the fact that the lost motion connection enables the children to get the frame started and rotating rather fast before the connectors begin to wind about the pole and create forces in direct opposition to their efforts. Once started, it is relatively easy to keep the frame rotating in spite of these opposing forces.

From the foregoing description of the several useful and novel features embodied in the improved elevating merry-go-round of the present invention it will be seen that the many objects for which it was designed have been achieved. Although the invention has been described in connection with the specific forms thereof illustrated in the accompanying drawing, I realize that certain modifications may be made therein by those skilled in the art without departing from the true nature thereof. Therefore, it is my intention that the scope of protection afforded herein shall be limited only insofar as said limitations are expressly set forth in the appended claims.

25 What is claimed is:

1. In an elevating merry-go-round of the type including a stationary upright pole, a frame mounted on the pole for both rotational and upward and downward movement relative thereto, a member mounted at the top of the pole for relative rotation, and a plurality of angularly spaced flexible connectors suspending the frame from the pole, the improvement which comprises means interconnecting the member and the pole to permit limited relative rotation therebetween in order to facilitate rotation of the frame, said interconnecting means comprising a part mounted for movement with the member and a part mounted on said pole, said parts being arranged to cooperate following the limited relative rotation whereby the connectors will begin to wrap about the pole and elevate the frame.

2. In an elevating merry-go-round of the type including an upright pole, a frame mounted on the pole for both rotational and upward and downward movement relative thereto, and a plurality of angularly spaced flexible connectors suspending the frame from the pole, the improvement which comprises a cap mounted on the top of the pole for relative rotation, said cap having means depending therefrom for attaching the flexible connectors and pin means mounted for conjoint rotation with said cap, and stop means depending from the pole positioned to engage the pin means on the cap and stop the relative rotational movement between said cap and pole whereupon the flexible connectors will begin to wrap about the pole and elevate the frame after rotation thereof has begun.

3. In an elevating merry-go-round of the type including an upright cylindrical pole, a frame mounted on the pole for both rotational and upward and downward movement relative thereto, and a plurality of angularly spaced flexible connectors suspending the frame from the pole, said connectors being arranged to wrap around the pole and elevate the frame upon rotation thereof, the improvement which comprises bearing means carried by the frame and journaled for rotation on the pole, said means comprising a tubular member arranged in concentric relation on the pole and sized to provide an annular space therebetween and a ring attached inside the tubular member approximately midway between the ends thereof in contacting relation with the surface of the pole to form a bearing block.

4. A device in accordance with claim 3 in which the upper and lower ends of the tubular member are enclosed by flexible sealing members covering the annular space between the pole and tubular member.

5. A device in accordance with claim 3 in which the

relative dimensions of the pole and tubular member are such that the annular space formed therebetween is sized to receive a child's hand without danger of it being squeezed between said pole and tubular member while being rotated relative to one another.

6. A device in accordance with claim 3 in which the length of the tubular section is such that the portions thereof extending above and below the ring will prevent a child from reaching his hand into the annular space a sufficient distance to contact said ring.

7. In an elevating merry-go-round, an upright stationary pole, a plurality of angularly spaced flexible connectors hanging from the top of the pole, and a frame mounted on the pole for both rotational and upward and downward movement relative thereto, said frame having an upper ring attached to the lower ends of the flexible connectors and a lower ring spaced below the upper ring movable conjointly therewith, said rings being mounted in substantially concentric relation about the pole and mounted for rotation with respect to the pole, 20 said upper ring providing means for rotating and elevating the frame by twisting the connectors around the pole and said lower ring providing means for continuing rotation of the frame after the upper ring has become elevated to the point where it cannot be reached from 25 the ground, said lower ring being of a smaller diameter than the upper ring whereby the frame may be rotated simultaneously by different sized children, a cap mem-

ber from which said connectors hang mounted at the top of the pole for relative rotation, means interconnecting the member and the pole to permit limited relative rotation therebetween in order to facilitate rotation of the frame, said interconnecting means comprising a part mounted for movement with the member and a part mounted on said pole, said parts being arranged to operate following the limited relative rotation whereby the connectors will begin to wrap about the pole and 10 elevate the frame.
